DESIGN FOR A REGISTER OR SIMILAR ARTICLE

Morris Sanders, New York, N. Y., assignor to Minneapolis-Honeywell Regulator Company, Minneapolis, Minn., a corporation of Delaware

Application October 15, 1945, Serial No. 122,833

Term of patent 14 years

(Cl. D81—21)

To all whom it may concern:

Be it known that I, Morris Sanders, a citizen of the United States and a resident of New York, in the county of New York and State of New York, have invented a new, original, and ornamental Design for a Register or Similar Article, of which the following is a specification, reference being had to the accompanying drawing, forming a part thereof.

Fig. 1 is a perspective view of a register or similar article showing my new design;

Fig. 2 is a front elevational view thereof;

Fig. 3 is a top plan view thereof partly in section on the line 3—3 of Fig. 2.

I claim:

The ornamental design for a register or similar article, substantially as shown.

MORRIS SANDERS.
